BURNER POT

James L. Breese, Santa Fe, N. Mex., assignor to
Oil Devices, Santa Fe, N. Mex., a limited partnership organized under the Limited Partnership Act of Illinois

Application October 14, 1938, Serial No. 234,919

8 Claims. (Cl. 158—91)

My invention relates to an improved liquid fuel burner and the process of making it. One purpose is the provision of improved means for manufacturing such a burner.

5 Another purpose is the provision of a burner which shall be efficient in operation at all stages, from a low turn-down to a maximum flame, and which may be shifted from stage to stage without deposit of carbon or soot.

10 Another purpose is the provision of an improved means for supplying primary air to a pot type hydroxylizing burner in which a hydrocarbon is first vaporized by the heat of combustion, the gas so formed being first supplied with primary air insufficient for complete combustion, the primary mixture so formed being thereafter burned off by the addition of a supply of secondary air.

Other purposes will appear from time to time in the course of the specification and claims.

20 I illustrate my invention more or less diagrammatically in the accompanying drawing wherein:

Figure 1 is a vertical axial section through a burner;

25 Figure 2 is a section taken on the line 2—2 of Figure 1 on a reduced scale; and

Figure 3 is a plan view of the burner wall prior to its assembly into the burner and illustrating the arrangement of air inlet apertures therein.

Like parts are indicated by like symbols throughout the specification and drawing:

30 Referring to the drawing, I generally indicates the side wall of a burner prior to its assembly into a finished burner. It is preferably made from sheet metal stock with the apertures, as below described, punched or otherwise formed in it prior to its assembly in the burner.

As a preferred arrangement of apertures, I illustrate a plurality of rows including a bottom row 2, an intermediate row 3, an upper row of primary air inlet apertures 4, and a still higher row 5 of secondary air inlet apertures. 6 generally indicates an intermediate space between the rows 3 and 4 which is preferably left blank although it will be understood that under some circumstances a row of apertures may be inserted therein. Such a row, when used, would normally have no greater number of holes therein than the rows 2 or 4 and preferably would have an even smaller number of holes.

40 In assembling the device, the strip 1 may be formed into generally cylindrical form with the abutting edges 7 and 8 welded or otherwise secured together. The bottom member 9 is then welded to the lower edge 10 of the member 1.

45 It will be noted that the secondary air aper-

tures 5 are considerably more numerous than the apertures in the rows 2, 3 and 4. It will be understood that in the pot type burner of which the present is an example, the liquid fuel, hydrocarbon or the like, is vaporized by the heat of combustion going on above in the chamber generally indicated as A. As the vaporized hydrocarbon rises upwardly through the chamber A formed by the member 1 and the bottom 9, it receives a primary air supply through the rows of 5 apertures 2, 3 and 4. This air supply is sufficient to form an intermediate mixture ready for combustion upon receiving an additional supply of air but with insufficient air to support initial full combustion. The mixture thus formed of air and 10 vaporized hydrocarbon rises upwardly through the pot or chamber A and, when it receives the secondary air supply through the row of apertures 15 5, is ready for final and complete combustion.

I find it desirable to employ a baffle 11 in order 20 to permit a low or pilot turn-down. I find it practical to employ a simple ring with a central aperture 12, but this is merely an example of a baffle form as baffles of other forms are also practical. However, for purpose of illustration I 25 describe and show the annulus 11 with the central aperture 12.

In the normal use of the device, and when a maximum turn-down is desired, the fuel supply through the line 14 is reduced to a minimum by 30 any suitable valve means herein diagrammatically shown as 15. Enough fuel is admitted to maintain a small fire in the lower portion of the pot A. Any suitable baffling means such as the ring 11 is then effective to prevent down-draughts of air 35 from above which would disturb the characteristic mode of combustion above described. When the portion of the chamber A below the pilot ring 11 is completely filled with a hydrocarbon gas, or vaporized hydrocarbon, which is obtaining oxygen from the relatively few holes of the row 2 below the ring, and just the right amount completely to hydroxylize all of the gas in this area, the result is a clear smokeless blue flame burning at the mouth or aperture 12 of the pilot ring 11. 40 During this stage of combustion it is not important how the holes are spaced in the upper part of the chamber A, as the air coming through them plays no part in primary or final combustion.

When the operator, in order to get a higher fire, increases the flow of oil to a point where there is more vaporized hydrocarbon in the chamber below the pilot ring 11 than can be hydroxylized, then the hydrocarbon gases arise through 45 50 55

the hole 12 into the upper portion of the chamber. It is then very desirable to have them completely surrounded by an envelope of air. Part 5 of this air envelope hydroxylizes the hydrocarbon gas and the additional part burns the resulting gases to complete combustion without a trace of smoke or deposit of carbon or soot.

In the next stage, where a further increase of oil is fed to the burner, the rising gases become 10 so rich that they completely fill the burner chamber A. In that case, it is not important how the holes are spaced, providing they are relatively far apart.

However, in the intermediate stage it is exceedingly important to provide a maximum concentration of air at a level just above the baffle ring. I find it desirable, therefore, to provide some means for obtaining the desired maximum air concentration and a simple means for obtaining 20 it is to position a closely spaced row of holes as at 3 so that there is a very substantial air concentration or air envelope admitted about the rising stream of gas. However, I must obtain this maximum concentration without admitting too great a total supply of primary air to the space 25 above the baffle ring 11. I therefore find it desirable to provide an uneven distribution of apertures and to employ the substantially blank space 30 between the rows 3 and 4. The row 4, also, since no concentration of primary air at a higher level is called for, is provided with a relatively sparse distribution of air inlet apertures.

Finally, the completely hydroxylized mixture, when the burner is burning at full height, receives 35 an upper envelope of air through the apertures 5 and the process of combustion is completed with a full smokeless flame at or above the top of the chamber A. I also find that the concentration of air by the close spacing of apertures 40 in the row 3 increases the overall capacity of the burner because the location of the closely spaced row of holes 3 immediately above the bottom of the pot or chamber provides a maximum amount of heat which, in turn, evaporates a maximum amount of oil.

Under some circumstances it is desirable upwardly to tilt the uppermost row of apertures 5, in order to provide an upward and inward direction of the secondary air admitted through said 50 apertures. This may be done prior to the bending of the member 1 into its final generally cylindrical form, but it is preferably done after the pot is formed. In either event, I find it preferable to obtain the tilting by a positive deformation 55 of the metal about the aperture.

Similarly, the passages 2 of the lowest row may be downwardly inclined, which inclination is preferably but not necessarily done after the assembly.

It will be realized that whereas I have described and illustrated a practical and operative device and the process of making it, nevertheless many changes may be made in the size, shape, 65 number and disposition of parts without departing from the spirit of my invention. I therefore wish my description and drawings to be taken as in a broad sense illustrative or diagrammatic, rather than as limiting me to my precise showing.

For example, whereas I have illustrated two 70 pairs of rows of holes 2, 3 and 4, 5, the upper row of each pair being at some time in the course of combustion a source of secondary air, it will be understood that I may increase the height of the burner and increase the number of such pairs of 75 holes. I illustrate a baffle 11 between the lower

rows 2 and 3. It will be understood, of course, that I may employ baffling between the individual rows of other pairs if desired.

In any event, by employing the valve means 15 I may vary the supply of liquid hydrocarbon 5 delivered along the line 14. It will be understood that when a minimum supply is employed, the apertures 2 are the sole source of primary air and the apertures 3 provide the secondary air necessary to burn the mixture so formed. When 10 the oil supply is increased, the apertures 4 are added to the apertures 2 and 3, as a source of primary air, and the apertures 5 become the source of secondary air.

At either stage, it is highly advantageous to 15 have a maximum concentration of secondary air just above the zone of admission of the primary air.

Stated mechanically, my conception of varying the volume of the introduction of air at various 20 levels involves, in the particular form of the device shown, the employment of two pairs of rows of apertures. The lowest pair, including the apertures 2, 3, is located in a lower portion of the pot, the lowest row being below and the upper 25 row of the pair being above the baffle 11. Preferably the lowest row of apertures includes a smaller number of apertures than the row next above, whereby a minimum volume of air is admitted below the baffle and the maximum volume 30 is admitted just above the baffle. Then there is a relatively blank space between the primary air apertures 3 and 4. The highest primary row of 35 apertures 4 and the secondary apertures are shown in the particular form illustrated herein as constituting an upper pair of apertures quite widely spaced from the lower pair.

It will be understood, of course, that I may introduce the secondary air in some other fashion, but the particular arrangement herein shown is 40 practical and has the advantage of permitting the control of both primary and secondary air by apertures which may all be punched in the single blank illustrated in Fig. 3. These pairs of rows 45 of apertures constitute a practical and simple solution of my problem and provide a much more effectively operating pot than a pot in which the rows are uniformly distributed and in which the primary apertures are uniformly distributed in the various rows of primary apertures.

I claim:

1. In a device for burning liquid hydrocarbons, an open-topped pot having a bottom and a circumferential apertured wall, a baffle in a lower portion of said pot, means for delivering a liquid fuel to said pot, the wall of said pot below said baffle being provided with a plurality of primary air inlet apertures, the wall above the baffle being provided with air inlet apertures arranged in a plurality of rows, one row of said apertures being located above but closely adjacent the baffle, and another row or rows being located at a still higher level, the apertures of the row adjacent the baffle having a total area substantially greater than that of the apertures of the next upper row, whereby a maximum volume of air is admitted to the pot at a level adjacent but above the baffle, and means for supplying secondary air at a level adjacent the top of the pot.

2. In a device for burning liquid hydrocarbons, 70 an open-topped pot having a bottom and a circumferential apertured wall, a baffle in a lower portion of said pot, means for delivering a liquid fuel to said pot, the wall of said pot below said baffle being provided with a plurality of primary 75

air inlet apertures, the wall above the baffle being provided with air inlet apertures arranged in a plurality of rows, one row of said apertures being located above but closely adjacent the baffle, and another row or rows being located at a still higher level, the apertures of the row adjacent the baffle being more numerous and more closely spaced than the apertures of the upper row or rows, whereby a maximum volume of air is admitted to the pot at a level adjacent but above the baffle, and means for supplying secondary air at a level adjacent the top of the pot.

3. In a liquid hydrocarbon burner, a pot body having a generally cylindrical side wall and a bottom, means adjacent the top of the pot for supplying secondary air, and a plurality of primary air apertures located below said means in three horizontal rows, two of said rows being relatively closely spaced together in a lower portion of the pot, the third such row being spaced relatively closely to and below said secondary air inlet means, said third row being spaced above the top row of said first two mentioned rows of primary apertures by a space substantially exceeding the spacing between the two said first mentioned rows, and a centrally apertured pilot baffle located in said pot between the two lowest rows of primary air apertures, the lowest row of primary air apertures having a substantially smaller number of apertures therein than the row next above it.

4. In a device for burning liquid hydrocarbons, an open-topped pot having a bottom and a circumferential apertured wall, a baffle located intermediate the top and bottom of said pot, means for delivering a liquid fuel to said pot, means for delivering primary air, in relatively small volume, to the space beneath said baffle, means for delivering air, in substantially greater volume, to the pot immediately above said baffle, additional means for admitting the air to said pot above the baffle, said additional means being vertically separated from said last previously mentioned means by a substantial distance, and means for supplying secondary air, at a level adjacent the top of the pot.

5. In a device for burning liquid hydrocarbons, an open-topped pot having a bottom and a circumferential apertured wall, a baffle located intermediate the top and bottom of said pot, means for delivering a liquid fuel to said pot, means for delivering primary air, in relatively small volume, to the space beneath said baffle, means for delivering air, in substantially greater volume, to the pot immediately above said baffle, said means including a plurality of inlets arranged circumferentially about the pot at a level adjacent the baffle aperture, said pot having, above said inlets, a blank space of substantial vertical height, said pot having additional air inlets above said blank space, and means for supplying secondary air at a level adjacent the top of the pot.

6. In a device for burning liquid hydrocarbons, an open topped pot having a bottom and means for supplying fuel thereto, and a circumferential apertured wall, a generally horizontal partition means located intermediate top and bottom of the pot and dividing the interior of the pot into two chambers, said partition means having a generally central aperture through which the chambers communicate, the wall of the lower

chamber being provided with a plurality of air inlet apertures, the wall of the upper chamber being provided with a plurality of air inlet apertures, the pot wall having a series of apertures located adjacent the level and above the aperture in the partition, the apertures of said series being more closely spaced than the apertures in immediately adjacent portions of the pot wall of the upper chamber and having a combined area such that a concentration of air is admitted to the upper chamber at a level adjacent the level of delivery of vaporized fuel upwardly through the aperture in said partition means, and means for supplying secondary air at a level adjacent the top of the pot.

7. In a device for burning liquid hydrocarbons, an open topped pot having a bottom and means for supplying fuel thereto, and a circumferential apertured wall, a generally horizontal partition means located intermediate top and bottom of the pot and dividing the interior of the pot into two chambers, said partition means having a generally central aperture through which the chambers communicate, the wall of the lower chamber being provided with a plurality of air inlet apertures, the wall of the upper chamber being provided with a plurality of air inlet apertures, the pot wall of the upper chamber having a row of apertures located adjacent the level and above the aperture in the partition, the apertures of said row being more closely spaced than the apertures in the immediately adjacent portions of the pot wall of the upper chamber, and having a combined area such that a concentration of air is admitted to the upper chamber at a level adjacent the level of delivery of vaporized fuel upwardly through the aperture in said partition means, and means for supplying secondary air at a level adjacent the top of the pot, said partition means including a generally cylindrical guiding portion defining the connecting aperture between the upper and lower chambers.

8. In a device for burning liquid hydrocarbons, an open topped pot having a bottom and means for supplying fuel thereto, and a circumferential apertured wall, a generally horizontal partition means located intermediate top and bottom of the pot and dividing the interior of the pot into separate chambers, said partition means having a generally central aperture through which the chambers communicate and through which vaporized fuel from the lower chamber flows upwardly into the upper chamber, the wall of the lower chamber being provided with a plurality of air inlet apertures, the wall of the upper chamber being provided with a plurality of air inlet apertures, the pot wall having a series of air inlet apertures discharging adjacent the level at which the upwardly flowing vaporized fuel is discharged from the central aperture in the partition, the apertures of said series being more closely spaced than the apertures in immediately adjacent portions of the pot wall of the upper chamber and having a combined area such that a concentration of air is admitted to the upper chamber at a level adjacent the level of delivery of vaporized fuel thereto and means for supplying secondary air at a level adjacent the top of the pot.
